UNITED STATES PATENT OFFICE

2,026,462

CONTAINER FOR DISPENSING POWDER

John Coyle, Baltimore, Md., assignor to Continental Can Company, Inc., New York, N. Y., a corporation of New York

Application August 30, 1934, Serial No. 742,162

1 Claim. (Cl. 221—98)

The invention relates to new and useful improvements in a container for dispensing powdered materials and more particularly tooth powder.

5 An object of the invention is to provide a container having a measuring compartment from which the contents may be dispensed when said container is in substantially a horizontal position.

A further object of the invention is to provide 10 a container of the above type wherein the dispensing opening is of sufficient length to dredge the entire brush.

These and other objects of the invention will 15 in part be obvious and will be hereinafter more fully disclosed.

Referring to the drawing—

Figure 1 is a view in side elevation of the container;

Fig. 2 is a top plan view of the same;

10 Fig. 3 is a vertical sectional view of the container;

Fig. 4 is a sectional view taken on the line 4—4 of Fig. 3.

The invention broadly relates to a metal tooth powder dispensing container. The body portion of the container is preferably cylindrical in shape and has a reduced cylindrical neck portion attached to one end thereof. This neck portion is provided with a plurality of inset sections each 5 forming a pocket to receive a predetermined amount of powder when the container is inverted. A rotatable closure is provided for the neck which conforms to the exterior thereof and forms the outer wall of the measuring pocket. This closure 10 has a slot therein which is adapted to be turned into registry with said pocket for dispensing the contents thereof. All of the parts of the improved container may be die-shaped which is very cheap in manufacture and simple to assemble.

15 Referring more in detail to the drawing, the improved container includes a body portion 6 made in the usual manner of metal. Attached to the body portion at one end thereof is a dome-shaped portion 8 which terminates into a reduced 20 cylindrical neck portion 7. The neck portion 7 is provided with one or more inset sections 9. The sections 9 are formed by cutting the neck at uniformly spaced intervals along a line parallel 25 to the upper edge thereof and bending the metal

inwardly between said cuts and said upper edge to form semicircular measuring pockets 8, which open into the interior of the container as indicated at 10 for receiving predetermined amounts of powder therefrom.

30 A closure 11 is provided for the neck having a depending portion 12 which conforms to the exterior thereof and forms the outer wall for the measuring pockets. The closure 11 is mounted free to rotate about the neck and is retained thereon by the spinning of the lower edge 13 thereof into a suitable circumferential groove 14 in the neck. A suitable hand grip for turning the same is provided by the knurling of the upper end as indicated at 15. A slot 16 is made in the depending portion 12 of the closure for the neck which is adapted to be turned into registry with one of the pockets 8 for dispensing the contents thereof.

35 While four receiving pockets have been shown in the drawing, one would serve the purpose just as well. The advantage of four pockets being only in the shorter distance the closure would necessarily have to be turned to uncover a pocket.

40 It will be obvious that minor changes in the details of construction and the shaping of the parts may be made without departing from the spirit of the invention as set forth in the appended claims.

Having thus described the invention, what I claim as new and desire to secure by Letters Patent is—

45 A metal dispensing container comprising a body, an end secured to said body and having a cylindrical projecting neck portion, said neck being cut along a line parallel to the upper edge thereof and the metal between said cut and said upper edge being curved inwardly to form a pocket opening at its lower end into the container, whereby said pocket will be filled with powder when said container is inverted, and a closure having a depending portion conforming to the exterior of said neck and forming the outer wall of said pocket, said closure being rotatably secured to said neck portion and having a slot adapted to be turned into register with said pocket for dispensing the contents thereof.

JOHN COYLE.
